Primary Examiner — Paula Greene(74) *Attorney, Agent, or Firm* — Howson & Howson LLP(57) **CLAIM**

The ornamental design for a headphone cord sleeve, as shown and described.

DESCRIPTION

FIG. 1 is a perspective view of a first embodiment of a headphone cord sleeve according to our new design;

FIG. 2 is a front elevational view of the headphone cord sleeve of FIG. 1, the rear elevational view being a mirror image thereof;

FIG. 3 is a right side elevational view of the headphone cord sleeve of FIG. 2, the left side elevational view being a mirror image thereof;

FIG. 4 is a top plan view of the headphone cord sleeve of FIG. 2, the bottom plan view being a mirror image thereof;

FIG. 5 is a perspective view of a second embodiment of a headphone cord sleeve according to our new design;

FIG. 6 is a front elevational view of the headphone cord sleeve of FIG. 5, the rear elevational view being a mirror image thereof;

FIG. 7 is a right side elevational view of the headphone cord sleeve of FIG. 6, the left side elevational view being a mirror image thereof;

FIG. 8 is a top plan view of the headphone cord sleeve of FIG. 6, the bottom plan view being a mirror image thereof;

FIG. 9 is a perspective view of a third embodiment of a headphone cord sleeve according to our new design;

FIG. 10 is a front elevational view of the headphone cord sleeve of FIG. 9, the rear elevational view being a mirror image thereof;

FIG. 11 is a right side elevational view of the headphone cord sleeve of FIG. 10, the left side elevational view being a mirror image thereof; and,

FIG. 12 is a top plan view of the headphone cord sleeve of FIG. 10, the bottom plan view being a mirror image thereof. The headphone cord sleeve has been shown broken in each of FIGS. 1-3, 5-7 and 9-11 to indicate indeterminate length.
